UNITED STATES PATENT OFFICE.

ALFRED J. HIRTHLER AND JOHN DREISTADT, OF WILKES-BARRE, PENNSYLVANIA.

CARTRIDGE FOR BLASTING POWDER.

Application filed October 8, 1924. Serial No. 742,413.

To all whom it may concern:

Be it known that we, ALFRED J. HIRTHLER and JOHN DREISTADT, citizens of the United States, residing at Wilkes-Barre, in the 5 county of Luzerne and State of Pennsylvania, have invented certain new and useful Improvements in a Cartridge for Blasting Powder, of which the following is a specification.

10 This invention relates to improvements in cartridges, which are principally used for holding the blasting powder for use in coal mines and the like.

One of the important objects of the present 15 invention is to provide a cartridge of the above mentioned character, which is provided with a water proof coating, whereby the blasting powder is protected against moisture.

20 A further object of the invention is to provide a cartridge of the above mentioned character, which is simple in construction, inexpensive, strong and durable, and further well adapted for the purpose for which it is 25 designated.

Other objects and advantages of the invention will become apparent during the course of the following description.

In the accompanying drawing, forming a 30 part of this specification, and in which like numerals designate like parts throughout the same:

Figure 1 is a side elevation of the material used in constructing or forming the cartridge, and

35 Figure 2 is a sectional view, taken approximately on the line 2—2 of Figure 1.

In constructing the cartridges, an elongated strip of paper is folded longitudinally, 40 and the free edges thereof are cemented together, whereby a substantially flat tube 1 is provided. The seam formed by the overlapping free edges of the tube is indicated at 2. A similar elongated strip of paper is 45 also folded longitudinally upon itself and the free edges thereof are arranged in overlapping relation and are also cemented whereby an elongated flat tube 3 is provided, the seam formed by the overlapping free 50 edges of the same being indicated at 4.

The tube 3 is formed around the tube 1, so

that an inner and outer tube respectively will be provided. As is clearly illustrated in the drawing, the seam 4 of the outer tube 3 is disposed directly opposite the seam 2 of the inner tube 1. With the inner tube disposed within the outer tube 3, the same are moved through a hot paraffin bath, in any suitable manner, whereby the outer tube is thoroughly coated with the paraffin, thus providing a waterproof covering for the tubing.

The elongated piece of tubing is then cut in the desired length, depending upon the 65 various sizes of cartridges, so that any number of cartridges may be obtained from a single length of tubing. The cartridges thus formed may be filled with the blasting powder in the well-known manner, and are then ready for use in coal mines, stone quarries, 70 or the like. The water-proof coating on the outer tube 3, is indicated at 5 in the drawing.

A cartridge of the above mentioned character will protect the blasting powder contained therein against moisture, and furthermore the person handling the cartridges will be protected against any danger, due to the fact that the miner need at no time expose the blasting powder to a flame, when preparing a shot.

80 While we have shown the preferred embodiment of our invention, it is to be understood that various changes in the size, shape, and arrangement of parts may be resorted to, without departing from the spirit of the 85 invention, and the scope of the appended claim.

Having thus described our invention, what we claim is:

90 A cartridge for blasting powder including an inner and an outer flat tube formed of paper, the free edges of said tubes being cemented together in overlapping relationship, the outer end of one tube being disposed in an opposite direction from the 95 outer end of the other tube, and the overlapping ends of the tubes being disposed on the same sides of the tubes.

In testimony whereof we affix our signatures.

ALFRED J. HIRTHLER.
JOHN DREISTADT.
